UNITED STATES PATENT OFFICE.

HORACE E. WOOLERY, OF ST. PAUL, MINNESOTA, ASSIGNOR TO WOOLERY MACHINE COMPANY, OF MINNEAPOLIS, MINNESOTA.

WEED-BURNING DEVICE.

Application filed December 27, 1924. Serial No. 758,843.

My invention relates to weed burning devices and particularly to such devices mounted on a wheeled frame which can be propelled along railway tracks. It will be obvious, however, that the wheeled frame might be propelled directly over the ground without being run on rails. An object is to provide a device of this character which embodies a hood consisting of a metal shell lined with refractory material to protect the metal from the intense heat generated within the hood. Another object is to provide a device of this character in which a hood is supplied with a blast of air which during its passage picks up liquid fuel and thoroughly vaporizes it before it is delivered to the hood. Another object is to increase the efficiency of the device by providing Venturi tubes through which the blast of air passes.

20 The full objects and advantages of my invention will appear in connection with the detailed description thereof and the novel features embodied in my inventive idea will be particularly pointed out in the claims.

25 In the accompanying drawings which illustrate a practical embodiment of my invention, Fig. 1 is a side elevational view of the device. Fig. 2 is a sectional detail view of the fuel feeding part of the device. Fig. 30 30 is a view of the device in longitudinal vertical section.

35 Referring to the construction shown in the drawings, the device includes a frame mounted on a pair of front wheels 10 and a pair of rear wheels 12 adapted to run on rails of a railway track. The frame consists of a pair of bars 14 supported by the front wheels and a pair of bars 16 supported by the rear wheels, these bars extending up convergently and their upper ends being connected by a pair of horizontal, longitudinal beams 18, tied together by transverse rods 20. Secured to the beams 18 are two pairs of internally threaded collars 22 through which 40 40 pass vertical screw rods 24 to whose upper ends handwheels 26 are secured. The lower ends of these screw rods are rotatively attached to angle pieces 28 which are secured to a downwardly flaring hood, having an open bottom. This hood consists of a metal shell 30 whose rear side is reinforced by ribs 32. The interior of the metal shell is lined with a refractory lining which may consist of fire bricks 34 secured to the shell in any suitable manner. The front side of the hood

has an opening around which is secured a forwardly extending tubular member 36 within which is a mixing chamber 37. A blower 38 in the embodiment shown, is mounted on a separate car 40. The delivery tube 42 of the blower extends rearwardly and at its rear end is attached to a Venturi tube 44 having a constricted portion 46. The rear end of the Venturi tube 44 is in substantially the same vertical plane as the front end of the tubular member 36 but is considerably smaller and concentrically disposed so that air may be drawn into the member 36 from around the tube 44. Located within the Venturi tube 44 is a second and smaller Venturi tube 48 having a constricted portion 50 lying in the same vertical plane as the constricted portion 46. The tube 48 is carried by the upper end of a tubular member 52 which passes through the lower side of the tube 44 as best shown in Fig. 3 and as shown may be held in place by screw threaded engagement with the wall. The passageway from the member 52 into the tube 48 is contracted to provide a conical valve seat 54 for co-operation with a needle valve 56 carried by a stem 58 screw-threaded through the lower end of the member 52 so that the passageway into the tube 48 may be regulated with great precision. A pipe 60 leads through the side of the member 52 for supplying liquid fuel from any conveniently positioned tank.

30 The operation and advantages of my invention will now be understood. The cars carrying the hood and the blower may be propelled along the track by any suitable source of power. The blast of air delivered by the blower passes through the Venturi tube 44 and into the mixing chamber 37. A portion of this air passes through the smaller Venturi tube 48 and produces a suction which draws liquid fuel up from the tubular member 52 so that this fuel is delivered into the mixing chamber 37. Additional air is drawn into the mixing chamber through the annular space around the tube 44, and the liquid fuel is thoroughly mixed with air and is vaporized before it passes into the hood where it burns. The bottom of the hood is spaced only a short distance above the ground so that the intense heat generated in the hood causes weeds and grass over which the hood passes to burn very quickly. The hood is positioned forwardly upon its supporting 100 100 105 105 110 110

frame so as to be closer to the front wheels than to the rear wheels. During the forward movement of the car, the flame flows backwardly and the forward placing of the hood prevents the heat from having an injurious effect on the rear wheels and supporting structure. The interior of the hood is subjected to such intense heat that the metal shell is apt to become buckled and soon destroyed unless some means is adopted to prevent this. Heretofore water has been placed on the outside of the hood but such method does not keep the flame from contact with the inside surface of the metal shell. Furthermore, the intense heat drives off the water in the form of steam with resultant waste of heat and it also requires time and labor to replace the water. These defects are overcome by providing the metal shell with a refractory lining such as fire brick. In the operation of the device the effect of the air blast from the blower is increased by the provision of the two Venturi tubes one inside of the other and having their constricted portions lying in a common plane. This causes an adequate supply of liquid fuel to be drawn up from the tube 52 in amount which can be regulated with great nicety by turning the needle valve. Thorough mixing of the air with liquid fuel occurs in the mixing chamber 37 and intense heat is produced within the hood with a relatively small amount of fuel. The distance of the hood from the ground may be readily varied by turning the hand wheels 26.

I claim:

1. A weed burning device comprising a wheeled frame, a metal shell constituting a hood supported from said frame and having an open bottom in proximity to the

ground, a refractory lining for the top and sides of said metal shell extending to the bottom of the latter, the front wall of said hood having a single large opening thru the metal and refractory lining, a tubular member connected with said opening, said tubular member constituting a mixing chamber, a blower, a delivery tube extending from said blower for delivering a blast of air into said mixing chamber, and a supply pipe for delivering liquid fuel into position to be picked up by said blast of air.

2. A weed-burning device comprising a wheeled frame, a hood supported from said frame and having an open bottom in proximity to the ground, a tubular member leading into said hood and extending forwardly therefrom, said tubular member constituting a mixing chamber, a blower, a delivery tube extending from said blower for delivering a blast of air into said mixing chamber, a Venturi tube positioned concentrically within said delivery tube, and means for supplying liquid fuel to said Venturi tube.

3. A weed burning device comprising a wheeled frame, a hood supported from the forward portion of said frame so as to be disposed considerably in advance of the rear portion of the frame, said hood having an open bottom in proximity to the ground, a tubular member extending forwardly from said hood and constituting a mixing chamber, means for producing a combustible gaseous mixture of air and liquid fuel in said mixing chamber, and a blower for forcing said gaseous mixture into said hood.

In testimony whereof I hereunto affix my signature.

HORACE E. WOOLERY.
